WALTER M. CROSS, OF KANSAS CITY, MISSOURI, ASSIGNOR, BY MESNE ASSIGNMENTS, TO GASOLINE PRODUCTS COMPANY, INC., OF WILMINGTON, DELAWARE, A CORPORATION OF DELAWARE

PROCESS AND APPARATUS FOR CONVERTING HYDROCARBONS

Application filed March 11, 1925. Serial No. 14,642.

This invention relates to improvements in a process and apparatus for converting hydrocarbons, and refers more particularly to a process in which cracking stock is subjected to conversion temperatures and high pressures during treatment, said conditions being regulated to effect the conversion of the oil in substantially the liquid phase. The process is preferably operated continuously for the production of relatively light gasoline like products from heavier stocks such as gas oil, kerosene distillate, fuel oil, refinery slops or other suitable cracking stocks.

Among the objects of the invention are, to provide a process in which the oil is heated in a coil to a cracking temperature and is transferred while in a highly heated condition to a stage of conversion wherein it is collected in a body and polymerization and cracking permitted to continue to the desired extent,—this heat and conversion taking place under high pressures, that is, sufficient pressures that will prevent any substantial vaporization during the heating or cracking period; to provide a process in which the cracked products are subsequently cooled on being withdrawn from the reaction stage and while in a cool condition the inert gases are separated from the liquids and the cool cracked material—or what we choose to term as “crude equivalent” or “synthetic crude”—is returned and utilized as a cooling medium for the highly heated oil as it is discharged from the reaction stage, this acquired heat being sufficient to distill off the lighter fractions from the synthetic crude whereby a liquid end point distillate may be obtained by proper dephlegmation and condensation; to provide a process, the novelty of which lies to a great extent in the cooling of the synthetic or cracked products and separating the gas from the hydrocarbon subsequent to cooling, thereafter returning the liquid synthetic crude to be reheated by the cracked products as they are discharged from the reaction stage in a highly heated condition; to provide an apparatus for carrying out this process and, in general, to provide a process and apparatus hereinafter explained in more detail.

The single figure is a diagrammatic side elevational view of the apparatus, with parts broken away and parts in section, in which the process may be practiced, although it is recognized that similar processes within the scope of the invention may be carried out in apparatuses of a different character without departing from the spirit of this invention.

Referring to the drawing, at 1 is shown a furnace preferably heated by means of gas burners diagrammatically shown at 2. In the furnace is mounted a continuous coil, the upper portion of which is designated as a preheating coil 3 and the lower bank, the heating coil 4. At 5 is shown a reaction chamber connected to the discharge end of the heating coil by a transfer line 6. The heat exchanger 7 is connected to the discharge line 8 of the reaction chamber. At 9 is shown a separator and at 10 a storage tank which may be provided with a vent 10'. At 11 is shown an evaporator connected by a vapor line 12 to the refluxing tower 13 which is preferably of the bubble type as shown diagrammatically in the broken away portion. A condenser 14 serves to liquefy the overhead material from the top of the tower 13 conducted thereto through the vapor line 15 and condenser coil 16 and at the same time to cool the unvaporized material withdrawn from the evaporator 11 through the line 17 and circulated through the condenser box through the cooling coil 18. At 19 is a reflux condensate reboiler, whose function is to redistill the lighter fractions by means of heat extracted from the reheated synthetic crude which is circulated therethrough in a closed coil shown at 20,—the evolved vapors being returned to the tower 13 through the line 21.

Describing briefly the mode of operation, the charging stock is supplied to the system through a line 22 and pump 23. This stock may be introduced by being circulated through a closed knock-back coil 24 positioned in the top of the tower, or may be bypassed automatically through the line 25 due to manipulation of a valve 26 by means of an automatic temperature regulator posi-

tioned in the top of the tower at the point of vapor exit designated as 27. This automatic pressure regulator may be a thermos-tick which, through electrical connections shown diagrammatically, operates the valve 26 to bypass the charging stock when the temperature of the overhead vapors is reduced to the predetermined point. This charging stock, whether circulated through the knock-back coil or bypassed through the line 25, is conducted through the line 28 to the suction side of the pump 29 from which it is discharged through the pipe 30 into the preheating coil 3, thence to the heating coil 4, and discharged in a cracking state into the reaction chamber 5. The conditions of heating in the cracking coil, that is, the velocity of the oil through the coil which constitutes the time factor of the heating and the degree of firing are properly controlled to prevent the accumulation of carbon deposition in the coils. These conditions are arrived at by proper temperature regulation, it being necessary to have sufficient heat in the oil to give an adequate yield after conversion in the reaction chamber 5, but such heating should not be excessive to produce objectionable carbon deposition in the coil. The reaction chamber is preferably fabricated of a single billet of steel forged to the desired shape on a mandrel, assuring the uniform texture throughout and a chamber which will withstand excessive temperatures and pressures. The usual size is approximately forty feet (40') long and four feet (4') in diameter. The end plates to the chamber are removable for cleaning purposes.

The oil, in its passage through the reaction chamber, is given sufficient time to consummate the conversion which was initiated in the coil. The cracked products are removed through the discharge line 8 and passed through the heat exchanger which is heavily insulated to prevent loss of heat by radiation. In its passage through the heat exchanger, the oil is introduced to the header 7^a, passing thence through the tubes 7^b into the header 7^c at the opposite end of the exchanger and being discharged in a relatively cool state through the line 31 controlled by a valve 32 into the gas separator 9. The valve 32 may be utilized to effect any predetermined reduction of pressure on the oil; preferably this is reduced to substantially atmospheric pressure. It will be understood that in the heat exchanger 7, sufficient heat is abstracted from the synthetic crude to reduce it to such a temperature as will preclude vaporization of the lighter or gasoline-like fractions upon the subsequent reduction of pressure. In the gas separator the incondensable products, including such gases as methane, ethane and the like, are returned through the gas line 33 controlled by a valve 34 to the burners 2. During

the initial stage of operation when the gas is insufficient to supply fuel to the burners, gas or fuel oil is introduced through the auxiliary line 35 regulated by a valve 36. The liquid material collected in the gas separator is automatically withdrawn through the line 37 by means of the liquid level regulator shown diagrammatically at 38. This liquid is discharged into the storage tank 10 from which it is recycled through the pipe 39 and pump 40 to the casing surrounding the heat exchanger by means of a line 41. By circulation about the tubes 7^b, this cooling medium acquires the heat contained in the oil in the cracked products discharged from the reaction chamber, and subsequent to the acquisition of this heat it is directed through the line 42 into the closed coil 20 positioned in the reflux reboiler 19. In this stage, it gives up a portion of its heat to the reflux condensate hereinafter explained in more detail. The discharge 43 from the coil 20 is connected into the bottom of the evaporator 11 where the oil is permitted to expand,—the lighter fractions passing off in the form of vapors which proceed through the vapor line 12 to the dephlegmator or refluxing tower 13. The unvaporized liquids are automatically withdrawn through the line 17, and after passing through the cooler 18 are conducted to storage. In the bottom of the evaporator is positioned a heating element such as a resistive element or electrode 44 heated by an electric current passed therethrough. It may be necessary to add heat at this point in the process according to the effectiveness of the heat exchange produced in the heat transfer element designated as 7. With certain types of oil, the exchange is sufficient to eliminate the additional heating in the evaporating tower, but provision is made in order to have a more efficient control of the operating conditions.

The vapors, passing overhead from the evaporator, are subjected to a dephlegmating action in the tower 13. The tower is of the well known bubble type wherein a series of vertically arranged pools of liquid oil serve as a percolating medium for the vapors. The condensate separated out in the respective pools gravitates downwardly in an opposed direction to the rising vapors. As previously described, the temperature of the overhead vapors passing off from the top of the tower is controlled by the automatic temperature regulator 27 which permits or prevents the flow of cool charging stock through the knockback coil 24. The vapors passing out through the top of the tower are directed to the line 15 and are liquefied in the coil 16, after which they are conducted to gasoline storage.

The reflux condensate which gravitate to the bottom of the tower passes off through the line 45 and is maintained at a definite level in the reflux reboiler 19 by means of the

automatic liquid level regulator 46 controlling the valve 47 in the draw off line 48. This level regulator maintains a liquid level which keeps the closed heating coil 20 immersed in the condensate. Thus, sufficient heat is transferred to the liquid body, driving off the vapors through the line 21 back to the tower 13 to be retreated with the vapors from the evaporator 11. The unvaporized material discharged through the line 48 returns to the suction side of the pump 29 and is combined with the charging stock to be recycled through the system for retreatment.

It is desirable to maintain the highly heated cracked products discharged from the reaction chamber at the pressure of the reaction chamber up to their discharge in a cooled condition from the heat exchanger. It is a well known fact that a better heat exchange can be effected by a liquid product than by a vapor. As an illustrative run on a process of this character, temperatures of from 600° F. to 1,000° F. are used in the heating coil. Normally, the discharge temperature from the coil is in the neighborhood of from 750° F. to 900° F., depending upon the character of the oil treated. A loss of heat of from 50° F. to 100° F. will take place in the reaction chamber in spite of the fact that it is heavily insulated. Pressures in the heating and reaction zones will normally range from 500 to 1500 pounds per square inch,—normal operating conditions being from 600 to 800 pounds per square inch. In starting the plant the storage tank 10 should be partially filled in order that there will be a cool medium to be recycled to take up the heat of the cracked products as they are discharged from the reaction stage.

Particular advantages of this type of operation lie in the fact that the cooling of the synthetic crude in this manner permits a somewhat more complete polymerizing effect in the crude equivalent, and further, the separation of the gas prior to its redistillation removes from the hydrocarbon products a considerable volume of volatile material which is relatively inert to the selective fractionations to which the vapors are subjected during the dephlegmating and refluxing treatment. The presence of these inert gases in the vapors necessitates a larger tower construction in order to properly treat the increasing volume,—a considerable portion of which is unaffected by dephlegmation. By removing these gases prior to redistillation, the volume of the vapors formed on redistillation is reduced to an extent that the size of the tower construction may be considerably decreased, thereby reducing the construction costs. In fact, both the evaporator and tower construction which comprises the redistilling units may be reduced in size, decreasing further the constructional expense.

This elimination of the vapor contamination by relatively inert gases is of considerable importance in the effectiveness of the treatment of the evolved vapors distilled from the synthetic crude.

70

I claim as my invention:

1. A process for converting hydrocarbons, comprising the steps of heating and digesting the oil at relatively high temperatures and pressures, withdrawing the cracked products while in a highly heated condition, cooling said cracked products in a heat exchanger stage and utilizing the heat given up in the heat exchanger stage to reheat the cooled products to a temperature sufficient to distill off the lighter constituents, passing said reheated products to stages of vaporization, dephlegmation and final condensation serially connected, utilizing a portion of the heat of the reheated oil to revaporize the oil constituents separated out during dephlegmation.

75

2. A process for converting hydrocarbons, comprising the steps of heating and digesting oil at high temperatures and pressures, passing the cracked oil in the highly heated condition through a cooling stage, separating the incondensable gas therefrom and recycling the cooled cracked oil to the cooling stage and there utilizing it as a medium to extract the heat from the cracked products, whereby it is raised to a distilling temperature, passing the reheated oil to and through evaporating, refluxing and condensing stages, and redistilling the condensate separated out in the refluxing stage by heat applied from the reheated oil prior to its introduction to the evaporating stage.

80

3. A process of converting hydrocarbon oil comprising heating and digesting the oil at relatively high temperatures and pressures, withdrawing the products of conversion in a highly heated condition and passing them through a heat exchanging stage and then through a gas separating stage maintained at a lower pressure than the heat exchanger; passing the liquid products recovered from the separating stage through the entire exchanger in heat transfer relationship to the hot products of conversion, then evaporating the reheated products of conversion, refluxing the vapors, passing reflux condensate in heat exchange relationship with the reheated liquid products from the separating stage, taking off vapors, recycling a portion of the reflux bottoms to the conversion zone and condensing the final products.

85

4. A process of converting hydrocarbon oil comprising heating and digesting the oil at relatively high temperatures and pressures, withdrawing the cracked products in a highly heated condition, and passing them through a heat exchanger maintained under substantially the same pressure as the digest-

ing stage, reducing the pressure on the cooled products in a gas separating stage, withdrawing the separated liquid products and passing them through the heat exchanger to abstract heat from the liquid products of conversion, then evaporating the reheated products of conversion, refluxing the vapors, redistilling reflux condensate by heat exchange with the reheated separated liquid products and recycling reflux bottoms to the heating and digesting means.

5. In an apparatus for converting hydrocarbons, the combination with means for cracking oil without substantial vaporization, comprising heating, digesting, evaporating, dephlegmating and condensing means serially connected, of a heat exchanger and separator interposed between the digesting and evaporating means and in fluid communication therewith, said heat exchanger being connected to the digesting means and adapted to cool the cracked oil and reheat the cooled separated oil and means connected to the exchanger adapted to redistill the reflux condensate discharged from the dephlegmating means.

6. In an apparatus for converting hydrocarbons, a combination with means for cracking oil without substantial vaporization comprising heating, digesting, evaporating, dephlegmating and condensing means serially connected, of a heat exchanger interposed in the discharge line from the digestion means and adapted to cool the cracked oil prior to gas separation and to reheat the cooled oil directed therethrough, and separate means connected with the exchanger for utilizing a portion of the heat of the reheated oil for redistilling the condensate separated out in the dephlegmating means.

7. A process of converting hydrocarbon oil comprising, passing oil in heat exchange relationship with hot vapors to preheat the oil, then further heating and digesting the oil at relatively high temperatures and pressures, withdrawing the products of conversion in a highly heated condition and passing them through a heat exchanging stage and then through a gas separating stage maintained at a lower pressure than the heat exchanging stage; passing the liquid products recovered from the separating stage through a heat exchanging stage in heat transfer relationship to the hot products of conversion, then evaporating the reheated products of conversion, refluxing the vapors, passing the reflux condensate in heat exchange with the reheated liquid products from the separating stage, taking off vapors therefrom and recycling a portion of the reflux bottoms to the conversion stage.
